CLOSURE FOR CONTAINERS

Frank I. Remy, Syracuse, Ind.

Application February 17, 1934, Serial No. 711,716

9 Claims. (Cl. 221—60)

This invention relates to a closure for a container for liquids, pastes and the like, and is an improvement over the closure disclosed in the copending application filed by me jointly with Benjamin P. Remy on January 14, 1933, Serial No. 651,776, entitled Closure for containers.

The object of the invention, and as set forth in the above-mentioned application, is to provide a sealed closure which is fluid-tight when closed, and which may be conveniently opened and closed by a slight turning movement of the cap without removing any part thereof from the container. Furthermore, it embodies a non-removable cap which when in one position closes and seals the nozzle of the container, and while in the other position is retracted to permit the nozzle to protrude therethrough so that the cap will not become fouled by the contents of the container when discharged.

The present invention resides in the structural features of the closure, wherein it is simple in design, compact, sturdy and cheap to manufacture in quantity production. It will be appreciated that in closures of this type three essential features are involved to make it commercially practical and of benefit to the public.

Firstly, the closure must be compact and conveniently small so as not to loom bulkily over the container, particularly wherein the public is accustomed to comparatively small closures. This is accomplished by permitting the sealing valve to move downwardly to one side between the cap and nozzle rather than be swung laterally so as to require substantial space between the cap and nozzle.

Secondly, it is essential that the structure be rugged and fool-proof since the constant operation thereof in opening and closing the container should not affect its working parts to such a degree as may destroy its usefulness and thereby the usefulness of the container before it is emptied of the contents.

Thirdly, and perhaps most important, the closure must be so designed as to permit of very cheap quantity production. In many instances the containers themselves are produced for only a few cents and the usual closures therefor for small fractions of a cent. Therefore, for commercial purposes, and to obtain any practical benefit to the public, a closure of this character must be produced within a reasonable margin of the cost of the container and the usual type of cap or closure.

The full nature of the invention will be un-

derstood from the accompanying drawing and the following description and claims:

In the drawing, Fig. 1 is a top plan view of the closure mounted on the end of a collapsible tube. Fig. 2 is an enlarged view showing the left half of the upper end of the tube and nozzle in central vertical section with the right half in elevation. Fig. 3 is an enlarged view showing the closure mounted on the tube and nozzle in open or discharging position. Fig. 4 is the same as Fig. 3 showing the closure in closed position. Fig. 5 is a section taken on the line 5—5 of Fig. 4.

In the drawing there is illustrated a collapsible tube 10 having its lower end spread out as indicated at 11 to provide a permanent bottom closure. The upper end of the tube is formed with a neck 12 and a discharge nozzle 13, the nozzle being surrounded by an annular cup 14 about which the closure is secured.

The closure comprises a cap 15 having a knurled side wall indicated at 16, and a central aperture in the top indicated at 17 through which the nozzle 13 is adapted to protrude when in open position, as illustrated in Fig. 3.

Frictionally secured within the cap 15 there is a compressible band 18 having split ends, as indicated at 19 in Fig. 5, to permit the band to be compressed within the cap 15 and expand therein to secure the structure in position. Said band is provided on opposite sides thereof with inwardly extending bosses 20 adapted to extend through a cam-like slot 21 formed about the opposite side walls of a collar 22. The collar 22 is formed about its lower edge with a series of teeth 23 adapted to surround the cup 14 and extend into a groove 24 thereof to be crimped and secured thereabout for locking the closure on the container. Said collar is provided with free ends, as indicated at 22a, for permitting it to be compressed within the compressible band 18.

Mounted within the collar 22 and pivotally supported upon the bosses 20 there is a valve cap 25 provided with a cork insert 26, said valve cap being concave to extend over the open end of the nozzle 13 for sealing the same. The cap terminates in a pair of downwardly curved arms 27 through which the bosses 20 extend to provide the pivotal support for the valve. Each of said arms is provided with a cut away portion 50 providing shoulders 28 adapted to be engaged in the actuation of the closure by the inwardly projecting lugs 29 for manipulating the valve, as hereinafter described.

In operation, assuming that the closure is in

closed position, as illustrated in Figs. 4 and 5, the container is held fixedly with one hand, while the forefinger and thumb are placed about the knurled surface of the cap 15, which is thereby 5 turned counterclockwise to open the closure. In thus turning the cap, the collar remaining stationary, the bosses 20, extending from the cap through the slots 21 in the collar, are carried throughout the length of their respective cam 10 slots 21 in the stationary collar. As will be noted in Fig. 4, the first counterclockwise movement carries the bosses upwardly in the initial upwardly extending portions of the slots 21 which acts to lift the cap and valve free of the nozzle. Continued counterclockwise movement carries the bosses through the laterally-extending portions of the slots 21, to a position where the lugs 29 are within the recess of the shoulders 28 15 formed in the arms of the valve. Continued movement causes the shoulders 28 to engage the lugs 29, whereby further relative movement between the shoulders 28 and lugs 29 act to swing the valve cap 25 about the pivotal mounting of the lugs to the position shown in Fig. 3. Further counterclockwise movement causes the 20 bosses 20 to travel through the downwardly-extending portion of the cam slots 21 to lower the cap and permit the uncovered end of the nozzle to protrude through the aperture 17 to permit 25 free discharge of the contents without fouling the closure.

By a clockwise rotation, the reverse action takes place, the cap travelling upwardly until the top thereof extends over the top of the nozzle, 30 whereupon the lugs 29 are engaged by the opposite shoulders 28 to swing the cap 25 upwardly over the end of the nozzle. Continued clockwise movement causes the bosses to pass through the downwardly-extending portion of their respective cam slots to cause the valve cap to be drawn tightly over the nozzle so that the cork gasket 26 is held in sealed engagement therewith.

The invention claimed is:

1. In a container having a nozzle protruding 45 therefrom, a closure therefor comprising an apertured cap through which said nozzle is adapted to extend when said closure is in open position, a fixed collar secured about said nozzle provided with cam slots therein, bosses associated with 50 said cap extending through said cam slots to permit rotation of said cap on said collar, a valve pivotally mounted on said bosses within said collar, and means for swinging said valve about its pivotal mounting to open and closed position 55 relative to said nozzle upon rotation of the cap.

2. In a container having a nozzle protruding 60 therefrom, a closure therefor comprising an apertured cap through which said nozzle is adapted to extend when said closure is in open position, a fixed collar secured about said nozzle provided with cam slots therein, bosses associated with 65 said cap extending through said cam slots to permit rotation of said cap on said collar, a valve pivotally mounted on said bosses within said collar, and a projection on said collar adapted to be engaged by said valve upon rotation thereof with the cap causing said valve to swing about its pivotal mounting to open and closed position 70 relative to said nozzle.

3. In a container having a nozzle protruding 75 therefrom, a closure therefor comprising an apertured cap through which said nozzle is adapted to extend when said closure is in open position, a fixed collar secured about said nozzle provided with cam slots therein, bosses associated with

said cap extending through said cam slots to permit rotation of said cap on said collar, a valve comprising a concave cap and downwardly curved arms pivotally supported upon said bosses within said collar, and means for swinging said valve through an arc so as to extend over said nozzle for closing the same when swung to one position and between said nozzle and cap when swung to the other position upon relative rotation in respect to said nozzle. 10

4. In a container having a nozzle protruding therefrom, a closure therefor comprising an apertured cap through which said nozzle is adapted to extend when said closure is in open position, a fixed collar secured about said nozzle in spaced relation thereto provided with oppositely-disposed cam slots therein, said cam slots being curved downwardly at both ends thereof, bosses associated with said cap extending through said cam slots to permit rotation of said cap on said collar and to cause vertical movement of the cap relative to the nozzle when rotated to and from its extreme positions, a valve pivotally mounted on said bosses within said collar, and means for swinging said valve about its pivotal mounting to embrace and seal the open end of the nozzle when in closed position and to occupy a position intermediate said nozzle and collar when moved to open position by relative rotation with respect to said nozzle. 20

5. A container having a nozzle, an annular cup of larger diameter positioned at the base of said nozzle, a closure therefor comprising a fixed collar having a plurality of teeth about the bottom edge thereof adapted to be clamped and rigidly 35 secured about said cup for permitting assembly thereof, a movable valve mounted in said closure, an apertured cap rotatably supported about said collar, and means for actuating said valve for moving it to open and closed positions relative 40 to the nozzle upon rotation of said cap. 30

6. In a container having a nozzle protruding therefrom, a closure therefor comprising an apertured cap through which said nozzle is adapted to extend when said closure is in open position, a band having oppositely-disposed inwardly-extending bosses formed thereon fixedly mounted within said cap, a collar fixedly secured about said nozzle in spaced relation thereto provided with oppositely-disposed cam slots curved upwardly about the periphery thereof through which said bosses extend for causing relative vertical movement upon rotation of the cap, a valve mounted within said cap with arms pivotally supported by said bosses, and means for swinging said valve about its pivotal mounting to open and closed positions upon relative rotation between said cap and collar. 55

7. In a container having a nozzle protruding therefrom, a closure therefor comprising an apertured cap through which said nozzle is adapted to extend when said closure is in open position, a band having oppositely-disposed inwardly-extending bosses formed thereon fixedly mounted within said cap, a collar fixedly secured about said nozzle in spaced relation thereto provided with oppositely-disposed cam slots curved upwardly about the periphery thereof through which said bosses extend for causing relative vertical movement upon rotation of the cap, a valve mounted within said cap with arms pivotally supported by said bosses, and means on said collar adapted to be engaged by the arms 60 of said valve for swinging said valve to and from 65

70

75

open position upon relative rotation between said cap and collar.

8. A container having a nozzle, an annular cup of larger diameter positioned at the base of said nozzle, a closure therefor comprising a fixed collar adapted to be rigidly secured about said cup for permitting assembly thereof, a movable valve mounted in said closure, an apertured cap rotatably supported about said collar, and means for 5 actuating said valve for moving it to open and closed positions relative to the nozzle upon rotation of said cap.

9. In a container having a nozzle protruding

therefrom, a closure therefor comprising an apertured cap member, a fixed collar member secured about said nozzle, one of said members being provided with cam slots therein, bosses associated with the other member extending through said cam slots to permit relative rotation of said cap member on said collar member, a valve pivotally mounted within one of said members, and means for swinging said valve about its pivotal mounting to open and closed 10 positions relative to said nozzle upon relative rotation of said members.
